CLAIM

The ornamental design for a golf bag stand, as shown and described.

DESCRIPTION

FIG. 1 is a front elevational view of a golf bag stand showing our new design;

FIG. 2 is a rear elevational view;

FIG. 3 is a side elevational view of the stand, the undisclosed side being a mirror image thereof;

FIG. 4 is a top plan; and,

FIG. 5 is a bottom plan.

The golf bag shown by means of broken lines in FIG. 3 is for illustrative purposes only.
